DOOR CHECK AND CLOSER

Johan David Sigfrid Larsson, Eskilstuna,
SwedenApplication September 29, 1942, Serial No. 460,137
In Sweden March 29, 1940

1 Claim. (Cl. 16—53)

The present invention refers to a hydraulic door check and closer having a spring adapted to shut the door, the shutting speed being controlled by a hydraulic braking device, and the details of the invention are substantially directed to the braking device, the securing of the spring and a simple and reliable means to facilitate the shutting of the door by a final impulse. Hereby the door-shutter according to the invention is rendered exceedingly simple, durable, safe in operation and cheap in manufacture.

The invention is illustrated on the accompanying drawing, wherein Fig. 1 shows a partly sectioned elevation of the door check and closer according to the invention. Fig. 2 is an elevation of a detail, and Fig. 3 shows a section on line *a—a* in Fig. 1.

Arranged within a casing 2 closed by a lid 1 is a cylindrical brake plunger 3 extending through the casing, said plunger being of uniform thickness and adapted to be rotated by means of a lever 4 connected to the door or doorcase. Flanges or fittings 5 are provided on the casing to secure the door check and closer to the doorcase or the door in a vertical position. The plunger is axially displaceable by the upper portion thereof being provided with threads 6 engaging corresponding threads in the lid. The bottom portion 7 of the casing is of an enlarged thickness, and provided therein is a tubular cylindrical bore 8 corresponding to the diameter of the plunger, said bore affording adequate guidance to the plunger which reaches the bottom thereof in all positions. The casing 2 is partly filled with some pressure liquid 9, such as oil of suitable constant viscosity. The plunger is provided with an axial passage 10 forming a seat 12 for a ball valve 11, said passage being angularly bent above the valve seat so as to reach the cylindrical surface of the plunger in a radial direction. The movements of the valve ball 11 are limited upwardly by the valve seat and downwardly by a transverse pin 13. The lower portion of the cylindrical bore is concentrically enlarged into an annular space 14 communicating through an angular passage 15 with the space for the pressure liquid above the bottom of the casing. The flow of the pressure liquid through the passage 15 is adapted to be controlled by means of a needle valve consisting of a screw 16 arranged in the lid 1, said screw having secured thereto a cylindrical rod 17 of the same diameter as that of the mouth of the passage 15 adapted to receive the end portion of the rod 17. This end portion of the rod is bevelled off on a plane

18 inclined to the axis of the rod. Thus there will be formed an opening on the lines of a circular segment in the mouth of the passage 15, the size of which opening is adapted to be minutely controlled by the turning of the screw from the position in which the needle valve is entirely open up to the position in which it is entirely closed. The pressure liquid escapes through said opening in a concentrated jet, which will bring about a soft operation, free from jerks, in the shutting of the door. Arranged about the brake plunger 3 is a powerful helical spring 19 bearing with its lowermost turns in a circular groove 20 in the bottom of the casing so as to be properly guided therein. The upper end 21 of the spring is bent radially inwardly and introduced into a corresponding transverse recess in the brake plunger, and the lower end 22 of the spring is bent axially downwardly and introduced into a corresponding recess in the bottom of the casing. Alternatively, the end portion 22 of the spring may be bent radially inwardly, a screw being then provided on both sides thereof, so that the heads of the screws are caused to squeeze said end portion securely in position. These means for the securing of the spring are entirely safe in operation and greatly facilitate the mounting and replacement of the spring.

Provided at a certain distance from the end of the plunger is an axial recess 23 of such a length that, when the plunger is near its lowermost position, an overflow passage is formed between the annular space 14 and the pressure liquid over the bottom of the casing.

The arrangements described operate as follows:

When the door is opened, the brake plunger is turned and at the same time displaced upwardly in the cylindrical bore, so that a sucking effect is produced therein, the valve 11 being thus opened and pressure liquid flowing into the annular space 14 through the passages 10 and 15, besides which the spring is brought under tension. When the door is then released, the spring will act in a closing direction on the door through the agency of the lever 4, the brake plunger then moving downwardly so as to exert a pressure in the annular space so that the valve 11 is closed and pressure liquid is forced out through the passage 15, wherein the needle valve controls and brakes the flow, so as to prevent the door from being shut too rapidly. When the door is nearly closed and the recess 23 of the brake plunger has come so far down that the overflow passage is formed, the liquid resistance

ceases, so that at the moment of shutting the door the spring only has the air resistance in the doorcase to overcome and the door is thus caused to be shut with a final impact, that is to say more rapidly, with a movement free from resistance during the very last portion of the shutting movement, which involves that the shutting of the door takes place more rapidly than if the plunger were to have a braking effect up to the moment the door was closed.

What I claim is:

A door check and closer comprising a cylindrical rotatable brake plunger provided with threads on the upper portion thereof in engagement with threads of an aperture in the lid, a helical spring about the brake plunger, the upper end of the spring being bent radially in-

wardly and introduced into a transverse recess in the brake plunger, and the lower end of the spring being bent axially downwardly and introduced into a recess in the thickened bottom portion of the casing, a tubular cylindrical bore in said bottom portion adapted to receive the brake plunger reaching down therein in all positions, an annular space concentric to the brake plunger in the lower portion of the cylindrical bore, an axial recess in the brake plunger arranged for a distance above the lower end of the brake plunger, the length of said recess being so adapted that, when the brake plunger is near its lowermost position, an overflow passage is formed between said annular space and the pressure liquid in the casing.
